UNITED STATES PATENT OFFICE.

JOSEPH N. PEW, JR., OF ARDMORE, PENNSYLVANIA, ASSIGNEE TO SUN OIL COMPANY, OF PHILADELPHIA, PENNSYLVANIA, A CORPORATION OF NEW JERSEY.

OIL TANK.

Application filed June 8, 1926. Serial No. 114,418.

In tanks containing petroleum and its distillates, particularly gasoline and light crude oil, serious losses occur through "breathing", which is caused by the formation and condensation of gas. It is known to provide means that allow gas to breathe from the tank to a separate gas receiver in the day-time and back again into the tank at night; the gas receiver being separated from the tank and containing an expandable and collapsible breather bag. The object of my invention is to provide a new, improved and substantially different means to guard against losses arising through breathing, said means being built into and forming part of the tank.

The accompanying drawing is a sectional elevational view of a tank embodying my invention in a preferred form.

20 The tank comprises a bottom *a*, a cylindrical wall *b*, internal steel columns *c*, which preferably extend above the tank and which are located some distance from the center of the tank, but nearer the center than the 25 circumference; an annular roof *d* which closes the tank between the columns *c* and the wall *b*; and an inside vertically slidible or otherwise movable tank comprising a cylindrical wall *e* and a dome-shaped roof *f* and having an open bottom. The inside tank is counterweighted by suitable means, for example, by weights *g* connected to the roof of the inside tank by means of flexible 30 connections *g* extending over pulleys *i* carried by a frame-work formed by the upper parts of the columns *c* and by cross-beams *j*. The construction of wall *b* may be the same as that of an ordinary oil tank, as, for example, sections of iron, steel or concrete, 35 welded or riveted together.

The roof *d* is formed in the shape of a flattened frustum of a cone; that is, it slopes upward from the wall *b* toward the inside tank at a small angle to the horizontal. The 45 roof, near its inner edge, is preferably inclined at a relatively large angle to the horizontal, and depending from its inside edge is a flange *k*, thereby forming in the main tank an annular gas pocket *m* surrounding 50 the inside tank.

Extending from the gas pocket *m* are pipes *n* (hereinafter called a gas line), which extend over the tank and down outside the tank and thence under the tank bottom, 55 where they join a vertical pipe *o* extending

up through the tank bottom and through the inside tank and terminating a short distance below the roof *f* of the inside tank.

The tank is also provided with an oil inlet pipe *p* communicating with a swing pipe *r*; an oil discharge pipe *s* extending vertically within the tank, preferably within the inside tank, and terminating at the desired oil level in the tank; a water inlet pipe *t*; a water discharge pipe *u* communicating with a swing pipe *v*; a vacuum relief *w* and a pressure relief valve *x*; and a float *y*. Extending from the upper end of swing pipe *r* is a cord 10, which extends over pulley 11 and around pulley 12 which is turned by means of a crank 13. Swing pipe *v* is operated by similar mechanism. Float *y* is used to operate controls which insure a definite level of liquid in the tank. These controls cause water to enter the tank as oil is pumped out and permit water to flow out as oil is pumped in. The controls need not be described, since they are well known in the art and form no part of the present invention.

The gases coming to the surface of the oil travel under the sloping roof *d* and into the annular pocket *m*. The slightest pressure arising from these generated gases drives the gases into gas line *n*—*o*, through which they flow into the space under the dome *f* and above the oil level. Owing to the weight of the inside tank being substantially just counterbalanced, a slightly increased pressure on the dome of the inside tank produced by these inflowing gases lifts the inside tank. Conversely, any slight gas condensation relieves the pressure on the dome of the inside tank and allows it to descend.

The tank will ordinarily be filled to the liquid level indicated in the drawing. Gasoline may be drawn off by pumping water through pipe *t* into the bottom of the tank, the gasoline flowing out through the overflow pipe *s*. The water is automatically discharged from the tank through pipes *u* and *v* when gasoline is pumped in through pipes *p* and *r*.

Having now fully described my invention, what I claim and desire to protect by Letters Patent is:—

1. An oil tank comprising a roofed main container and an inside floating container comprising a roof and an enclosing wall 110

adapted to extend below the level of the oil in the main container, the floating container being movable vertically to vary the gas capacity of the tank in accordance with variations in gas volume, and means providing for flow of gas between the upper part of the main container and the upper part of the inside container.

2. An oil tank comprising a relatively large roofed main container and a relatively small inside floating container comprising a roof and an enclosing wall adapted to extend below the level of the oil in the main container, the containers being arranged in substantially concentric relationship and in free communication to allow flow of liquid between them, and means allowing flow of gas between the gas spaces of the containers, the inside container being movable to vary its gas capacity in accordance with variations in gas volume.

3. An oil tank comprising a relatively large main container and a relatively small inside container, the same being arranged in substantially concentric relationship, the large container comprising an annular sloping roof and covering that annular part of the main tank outside the inside container, the latter comprising an enclosing wall and a closed top and movable vertically in accordance with variations in gas volume, and means allowing flow of gas between the annular space under the higher part of the roof of the main container and the space under the closed top of the inside container.

4. An oil tank comprising a relatively large main container and a relatively small inside container, the same being arranged in substantially concentric relationship, the

large container comprising an annular sloping roof and covering that annular part of the main tank outside the inside container, the latter comprising an enclosing wall and a closed top and movable vertically in accordance with variations in gas volume, and a gas pipe line extending between the annular space under the higher part of the roof of the main container and the space under the closed top of the inside container.

5. An oil tank comprising an outer wall and a roof, one section of which is movable vertically and another surrounding section of which is relatively fixed, the movable roof section carrying a depending cylindrical wall, and means allowing circulation of gas between the gas spaces under the two roof sections.

6. An oil tank comprising a relatively large main container and a relatively small inside container, the same being arranged in substantially concentric relationship, the large container comprising an annular roof sloping upward and inward at a relatively narrow angle to the horizontal throughout the greater portion of its width, that part thereof adjacent its inner edge and to the wall the inside container sloping inward and upward at a relatively wide angle to the horizontal and thereby forming an elevated annular pocket surrounding the inside container, the latter being movable to vary its gas capacity, and means allowing flow of gas between said annular pocket and the gas space of the inside container.

In testimony of which invention, I have hereunto set my hand, at Philadelphia, Pennsylvania, on this 7th day of June, 1926.

JOSEPH N. PEW, JR.
